UNITED STATES PATENT OFFICE.

JOSEPH F. EAGAN, OF ST. JO, TEXAS.

DESIGN FOR A BRACKET.

47,283.

Specification for Design.

Patented May 4, 1915.

Application filed January 25, 1915. Serial No. 4,387. Term of patent 3½ years.

To all whom it may concern:

Be it known that I, JOSEPH F. EAGAN, a citizen of the United States, residing at St. Jo, in the county of Montague and State of Texas, have invented a new, original, and ornamental Design for Brackets, of which the following is a specification, reference being had to the accompanying drawing, forming a part thereof.

Figure 1 is a perspective view of a bracket

illustrating my design, looking at one side thereof; and Fig. 2 is a perspective view looking at the other side of the bracket.

I claim:

The ornamental design for a bracket, as shown.

JOSEPH F. EAGAN.
